US00D865302S

(12) United States Design Patent (10) Patent No.: US D865,302 S
Kim (45) Date of Patent: * Oct. 29, 2019

(54) HARNESS FOR PETS

(71) Applicant: FASHION FACTORY CO. LTD.,
 Seoul (KR)

(72) Inventor: Il Ho Kim, Seoul (KR)

(73) Assignee: FASHION FACTORY CO. LTD.,
 Seoul (KR)

() Term: 15 Years

(21) Appl. No.: 35/505,956

(22) Filed: Apr. 27, 2018

(80) Hague Agreement Data

Int. Filing Date: Apr. 27, 2018
 Int. Reg. No.: DM/101096
 Int. Reg. Date: Apr. 27, 2018
 Int. Reg. Pub. Date: Nov. 2, 2018

(51) LOC (12) Cl. 30-04
 (52) U.S. Cl. USPC D30/152

(58) Field of Classification Search
 USPC D30/144, 145, 151, 152, 154;
 D29/101.1, 101.3, 101.4; D2/718, 719,
 D2/860, 861
 CPC A01K 27/002
